UNITED STATES PATENT OFFICE.

EDWIN O. KLEMM, OF DAYTON, OHIO, ASSIGNEE TO KLEMM MANUFACTURING COMPANY, OF FENTON, MICHIGAN, A CORPORATION.

TONE ARM FOR GRAPHOPHONES.

Application filed July 7, 1921. Serial No. 432,992.

To all whom it may concern:

Be it known that I, EDWIN O. KLEMM, a citizen of the United States, residing at Dayton, in the county of Montgomery and State of Ohio, have invented certain new and useful Improvements in Tone Arms for Graphophones, of which the following is a specification.

In the construction of talking machines such as are in common use today the large majority of such machines embody a tone-arm upon which the reproducer is mounted. The reproducer for the practical operation of the machine must be adapted for two main or essential movements, namely, a movement in a horizontal plane as when the reproducing stylus is operating over the surface of the record for purposes of reproduction, and a movement relatively vertical required in order to remove and replace the stylus respecting its engagement with the record. The last mentioned movement is manually compelled in regard to some machines, or automatically and mechanically compelled in those machines where automatic mechanism is employed to cause repeating action of the reproducer.

The most commonly used form of connection between the supporting base and the tone-arm is what is known as a ball and socket joint type, the same permitting a universal movement of the tone-arm and reproducer. This type of joint is rather complicated in its construction and requires the use of parts made with considerable precision or nicety. Also, such joints include parts which are located so that they interrupt at one place or another the continuous sound passage which leads from the reproducer, through the tone-arm, and to a suitable sound amplifier.

My invention comprises a special form of connection between the tone-arm and its supporting base, permitting the movements as required, as above stated, but simplifying the construction materially, and avoiding the use of parts which in any way project into or interrupt the sound passage through the tone-arm. In substance, I provide a simple hinge member applied to the base, equipped with a hinged leaf or plate, and rotatively attached to the supporting end of the tone-arm, the hinged leaf permitting the necessary vertical movement of the tone-arm and the rotative connection permitting the de-

sired horizontal turning movement of said tone-arm.

A full understanding of my invention will be readily had upon reference to the following detailed description, in conjunction with the accompanying drawings, in which:

Figure 1 is a fragmentary side view of the base upon which a turn table is mounted, reproducer and tone-arm parts, and my improved connection between the tone-arm and the base, said connection being partially shown in section.

Figure 2 is a rear elevation showing the essential parts of my invention illustrated in Figure 1.

Figure 3 is a view somewhat similar to Figure 1, omitting the base, and showing a modified construction utilizing the same principle as that involved in the figures above described.

Figure 4 illustrates by a perspective view still another form of hinging connection, alone, very similar to that illustrated in Figures 1 and 2.

In the drawings A denotes the base upon which the turn table or record carrier B is mounted. The reproducer is denoted at 1 and is carried by the tone-arm 2 which is of very simple angular formation, and provided with a continuous sound passage therethrough. The tone-arm 2 has a sleeve 3 rigidly connected thereto near its elbow and forming virtually a vertical extension downwardly of the main body of the tone-arm. The sleeve portion 3 of the tone-arm 2 fits upon a bearing sleeve 4 rigidly attached in any substantial manner to the lower horizontal arm 5 of the hinged leaf or plate 6. The leaf or plate 6 is hinged by a pintle rod 7 to a hinge member 8 attached by fastening screws 9 or the like, to the base 8. The parts 5 and 8 are provided with registering openings in their adjacent portions, such openings forming a continuation of the sound passage of the tone-arm 2.

Obviously from the foregoing the tone-arm 2 may swing upwards with the pintle 7 as an axis. There are provided between the sleeve 3 and the bearing sleeve 4 suitable ball-bearings 10 and 11, the latter being inserted into the ball race intermediate the parts 3 and 4, through an opening in the sleeve 3, which opening is normally closed by a screw 12. Normally there is a

slight space between the arm 5 and the horizontal portion of the hinge member 8, which space is sufficient to permit the play upwards and downwards of the reproducer 5 incident to the normal turning of the record carrier B with the record thereon, and incident to any such movement required by the warped condition of the record or record carrier producing a sort of waving of the 10 stylus in action.

I utilize a spring 13 surrounding the pintle 7 and suitably attached to the parts 4 and 6 so as to act upon these parts to counterbalance the weight of the tone-arm 2, an 15 effect which has been found desirable and which is utilized in a different way in tone-arm constructions at present in use.

Figure 3 illustrates a modified adaptation 20 of my invention wherein I utilize parts which correspond to those heretofore described, the tone-arm however being made in a continuous form and having a swivel or rotative connection at 14 provided by ball-bearings mounted in a suitable ball race 25 formed between the flange 15 at the lower extremity of the tone-arm and a bearing member 16 applied to the horizontal portion 17 of the hinged leaf 18. The leaf or plate 18 is of somewhat U form and has the bearing at 14 at the lower extremity of the tone-arm 2, and an additional bearing at 19 on the upper portion of the tone-arm just 30 above the elbow. The bearing 19 is a simple point bearing of a conventional form in itself. The leaf or plate 18 is pivoted by a pintle 20 intermediate the ends of the vertical portion of said plate to the hinge member 21 which corresponds very closely to the hinge member 8 of the construction before 35 described.

For certain types of phonographs it will be quite evident that the construction of Figure 3 affords a very simple, inexpensive, and practical mode of constructing and supporting the tone-arm device. The action of 45 the parts as to movements is self-evident.

In Figure 4 there is shown a construction hinge member 22 and hinged leaf or plate 23 which is almost identical with Figures 1 and 2, save that the vertical portions of 50 these parts are much attenuated, as to extent, and proportion. In some types of graphophones the construction of Figure 4 will be found useful and effective to admit of the desired movement of the tone-arm and reproducer required under practical conditions of use.

If will be observed that in effect the sleeve 3 is a continuation of the tone-arm 2 and if desired a continuous formation might be employed within the purview of this invention. Furthermore, with my construction, a very simple method of connecting the reproducer 1 to the tone-arm 2 may be em-

ployed, no special joint means being necessary to admit of the engagement of the reproducing means from the record.

Having thus described my invention what I claim as new is:

1. In combination a base for supporting 70 a tone-arm, a tone-arm, and means connecting the tone-arm with the base comprising a hinge located exterior to the sound passage of the tone arm, the hinge comprising complementary parts, one attached to the base, 75 and a rotative connection between the other part of the hinge and the tone-arm.

2. In means of the class described, the combination of a base support, a tone-arm mounted thereon, and a connection between 80 the base and tone-arm comprising a hinging device which consists of a hinge member secured to the base and having an upstanding portion, a hinged leaf carried by said upstanding portion and provided with an off-standing lateral arm, and a tone-arm movably connected with said lateral arm.

3. Means as claimed in claim 2, combined with a pintle forming a part of the connection mentioned, and a spring encircling 90 said pintle and engaging the hinge member and leaf to counterbalance the tone-arm.

4. In means of the class described, the combination of a base, a tone-arm having a vertically and downwardly extending supporting element, a bearing sleeve to which said element is rotatively applied and a hinging device supporting the bearing sleeve and including a hinge member secured to the base, together with a hinged leaf pivoted to 100 said hinge member and having an offstanding arm supporting said bearing sleeve.

5. Means as claimed in claim 4 wherein the hinge member has a base extension which is attached to the base and is located 105 beneath the arm of the hinged leaf, said two parts having registering openings forming continuations of the sound passage of the tone-arm.

6. In a machine of the class described, in 110 combination, a base having a sound opening therethru, a tone-arm having the usual sound passage therein, and formed with an elbow portion, a hinging device for the tone-arm comprising a hinge member secured to 115 the base and having an upstanding arm, a hinged leaf hingedly connected to said upstanding arm, and having a lateral arm, a sleeve bearing member carried by said arm having rotative engagement with the lower 120 portion of the elbow of the tone-arm, the opening in the base, the sleeve bearing member, and the sound passage being co-extensive so as to form a continuous unobstructed sound passage for the elbow portion of the 125 tone-arm and leading thru the base.

In testimony whereof I affix my signature.

EDWIN O. KLEMM.
